UNITED STATES PATENT OFFICE.

SAMUEL G. WILKES, OF WALLINGFORD, CONNECTICUT, ASSIGNOR TO R. WALLACE & SONS MFG. CO., OF WALLINGFORD, CONNECTICUT, A CORPORATION.

DESIGN FOR A COFFEEPOT OR SIMILAR ARTICLE.

Application filed January 20, 1928. Serial No. 24,946. Term of patent 14 years.

To all whom it may concern:

Be it known that I, SAMUEL G. WILKES, a citizen of the United States, residing at Wallingford, in the county of New Haven and State of Connecticut, have invented a new, original, and ornamental Design for a Coffeepot or Similar Article, of which the following is a specification, reference being had to the accompanying drawing, forming part thereof.

Fig. 1 is a side view of a coffeepot showing my new design; and

Fig. 2 is a top view of the same.

I claim:

The ornamental design for a coffeepot or similar article as shown.

SAMUEL G. WILKES.
